UNITED STATES PATENT OFFICE.

JOHN R. SUNDEE, OF BUFFALO, NEW YORK, ASSIGNOR TO EMPIRE JEWELRY CASE COMPANY, OF BUFFALO, NEW YORK, A CORPORATION OF NEW YORK.

APPARATUS FOR COVERING BOXES.

No. 879,599.

Specification of Letters Patent.

Patented Feb. 18, 1908.

Application filed April 6, 1907. Serial No. 366,714.

To all whom it may concern:

Be it known that I, JOHN R. SUNDEE, a citizen of the United States, residing at Buffalo, in the county of Erie and State of New York, have invented a new and useful Improvement in Apparatus for Covering Boxes, of which the following is a specification.

This invention relates to an apparatus for covering the body and the lid of a jewelry box or the like with a single piece of silk, velvet, leather or other suitable material.

Comparatively large jewelry boxes have heretofore been covered with a single piece of material by hand, but attempts to properly cover small boxes, such as finger-ring boxes, in that manner, have been unsuccessful owing to the difficulty of stretching the material sufficiently to properly cover the inner corners of the body and the lid, and also because of the limited space afforded to the fingers for this purpose and for folding the material over the edges of the box-members.

The object of my invention is the provision of a die or apparatus by which such small boxes can be neatly and completely covered in a convenient and expeditious manner.

In the accompanying drawings consisting of 2 sheets: Figure 1 is a perspective view of the apparatus. Fig. 2 is a similar view of the lower or die plate. Fig. 3 is a longitudinal section of the apparatus, showing a box and its covering pressed into the cavities of the die-plate. Fig. 4 is a cross section in line 4-4, Fig. 3. Fig. 5 is a perspective view of the die-plate, showing the box and the covering pressed into its cavities, and the covering cut on a line with the hinge, preparatory to folding and securing the same to the box-members.

Similar letters of reference indicate corresponding parts throughout the several views.

Referring to Fig. 3, A indicates the body of a finger-ring box, A¹ its hinged lid or cover and A² the one-piece covering of velvet or other suitable material.

My improved apparatus comprises a die or lower plate B and an upper plate C resting thereon, the two plates being preferably rectangular and of the same dimensions, as shown. One of the plates, preferably the lower one, is provided at its sides and ends with stops d, d¹ which overlap the upper plate and hold it against displacement on the

lower one. Means are also provided for removably holding the upper plate down upon the lower one, the preferred means shown in the drawings consisting of hooks E pivoted to the ends of the upper plate and interlocking with notches in the stop plates d¹ of the lower plate.

As shown in Figs. 1, 2 and 3, the lower plate B is provided with two sockets or cavities F, F¹ arranged side by side and having the proper shape and dimensions to receive respectively the box-body and the lid, together with the covering A². As the body of the box is shallower than the lid, the socket F¹ which receives the body is provided in its lower portion with a filling block f of suitable thickness, which rests upon the table or other support on which the apparatus is placed; or if preferred, said socket may be just deep enough to receive the box body.

The two sockets F, F¹ are separated by a comparatively thin partition g which terminates somewhat short of the upper surface of the die-plate B to leave room for the hinge of the lid when the box-members are pressed down into the cavity, as shown in Figs. 3 and 4. Located at the upper edge of this partition, at its junction with the walls of the sockets F, F¹, are a pair of lugs or ridges h which project above the upper surface of the die-plate and raise the covering A² above said surface when the body and the lid are pressed down into the sockets, thus leaving sufficient material along the hinge line of the box to fold into and completely cover the adjacent corners of the box-members. As shown in Fig. 2, the lugs h extend inwardly from the walls of the sockets F, F¹ a distance nearly equal to the distance from the sides of the box to the ends of its hinge, and the sides of the lugs are concave to conform to the rounded corners of the sockets.

The upper plate C is provided with a vertical slot or opening c which is as wide as the sockets F, F¹ and extends throughout the length of both of the same.

In covering boxes with the improved apparatus, the upper plate C is removed from the lower or die plate and a piece of covering-material of the proper size to cover both the box-body and the lid is laid face down upon the die-plate over its sockets F, F¹. The upper plate is next locked down upon the die-plate to hold the covering in place and prevent wrinkling thereof during the subse-

quent operations. After applying glue to the front and side walls of the body and lid of the box to be covered, the latter is placed in the slot of the retaining plate C with its hinge 5 resting on the portion of the covering lying upon the partition, the two members of the box being preferably held at an angle to each other, as shown by dotted lines in Fig. 3. The lid or deep, st member of the box is next 10 pressed down into the corresponding socket F of the die-plate by hand or otherwise, and the box-body is then pressed into the other socket F in the same manner. In forcing the box members into the die-cavities, the 15 covering is tightly stretched upon the members owing to the pressure exerted upon the covering by the upper plate which, however, does not tightly grip the covering but simply retards its displacement into the die-cavities. 20 After this pressing operation, the upper plate C is removed and the raised or bulged portions of the covering which overlie the lugs h are severed on a line with the center of the lugs, as shown at i in Fig. 5. A coating of 25 glue is next applied to the inner sides of the box-members and said divided portions of the covering together with the rest of the margin of the same are then properly trimmed and finally folded over the edges of the box- 30 members against their glued inner sides.

While this improved apparatus is especially desirable for applying a single-piece covering to the bodies and lids of small boxes, such as used for finger-rings, it may 35 also be used with advantage for covering larger boxes of various kinds.

I claim as my invention:

1. In an apparatus for covering boxes, a die-plate having cavities for receiving the body and the lid of a box, and means arranged at the adjacent inner corners of said cavities for supporting the covering-material above the surface of the die-plate, substantially as set forth.
2. In an apparatus for covering boxes, a die-plate having sockets or cavities for receiving the body and the lid of a box, and lugs or ridges arranged at the adjacent inner corners of said cavities and projecting above 45 the surface of the die-plate, substantially as set forth.

3. In an apparatus for covering boxes, a die-plate having sockets or cavities for receiving the body and the lid of a box, a partition separating said cavities, and lugs or 55 ridges arranged at opposite ends of said partition and projecting above the surface of the plate, substantially as set forth.

4. In an apparatus for covering boxes, a die-plate having sockets or cavities for receiving the body and the lid of a box, a partition separating said cavities, and raised lugs arranged at the junction of the partition and the walls of said cavities and conforming to the adjacent corners of the cavities, 65 substantially as set forth.

5. In an apparatus for covering boxes, a die-plate having sockets or cavities for receiving the body and the lid of a box, a partition between said cavities terminating short of the 70 upper surface of the die-plate, and lugs arranged at the junction of the partition and the walls of said cavities and projecting above the upper surface of the die-plate, substantially as set forth.

6. An apparatus for covering boxes, comprising a lower die-plate having a pair of cavities for receiving the hinged body and lid of a box, a retaining plate for the box-covering resting upon the die-plate and having an 80 opening which registers with said cavities, and stops arranged on one of said plates for holding the retaining plate against displacement on the die-plate, substantially as set forth.

7. An apparatus for covering boxes, comprising a lower die-plate having a pair of cavities for receiving the hinged body and lid of a box, a partition separating said cavities, lugs arranged at the junction of the partition and the walls of the cavities and raised above the upper surface of the die-plate, and a retaining plate resting upon the die-plate and having an opening which registers with said cavities, substantially as set 95 forth.

Witness my hand this 2d day of April, 1907.

JOHN R. SUNDEE.
